By his Attorney, H. M. Brown.

UNITED STATES PATENT OFFICE.

JOSEPH ROBISON, OF GREENBUSH, NEW YORK.

VAPORIZING AND IGNITION DEVICE.

SPECIFICATION forming part of Letters Patent No. 532,100, dated January 8, 1895.

Application filed August 16, 1894. Serial No. 520,536. (No model.)

To all whom it may concern:

Be it known that I, JOSEPH ROBISON, a citizen of the United States, residing at Greenbush, Rensselaer county, New York, have invented certain new and useful Improvements in Vaporizing and Ignition Devices; and I do hereby declare the following to be a full, clear, and exact description of the invention, such as will enable others skilled in the art to which it appertains to make and use the same, reference being had to the accompanying drawing, and to the figures and letters of reference marked thereon, which form a part of this specification.

The object of my invention is to provide a new and improved vaporizing and ignition device for oil or vapor engines.

In the drawing the figure shows a vertical sectional view of my device in operative construction.

The numeral 1 shows a casing preferably attached to the top of the engine cylinder 20 forming a chamber 1' which is practically an extension of the cylinder. To the top, preferably, of casing 1 I fix a valve casing 2 having an air inlet 19 and an oil supply pipe 9 entering it, and containing an automatic acting valve 3, constructed as follows: The valve stem 4 is tubular for part of its length, the balance being preferably solid. At the lower end of the stem 4 is a flange 3' having a stud 3''' depending from its lower side, the bore of the stem 4 being formed through the stud 3''' and its lower end closed by a plug "a." About the stud is screwed the washer 3'' and preferably reinforced by a nut turned against its under side. The meeting faces of the flange 3' and washer 3'' are grooved or channeled, the grooves or channels 3''''' communicating with the bore of the valve stem so that when a charge of oil is passed down the bore of the stem it will pass into the grooves 3''''' and out at their outer ends, which discharge around the edge of the valve. The valve stem 4 passes into and through chambered plug 6, and surrounding the stem preferably is a plunger 5 flanged at its upper end preferably, and abutting against a nut 8 turned on the stem, the valve 3, its stem 4 and the plunger 5 (being adjustable by means of nut 8) being held in position by the coiled spring 7, the plunger and stem being vertically mov-

able in the chamber 18 of the plug 6, the plunger 5 when in its normal position being set so that its lower end stands above port 5' in the stem 4, and so as not to fill the chamber 18 from the port to its bottom, an open space being left so that oil may fill it from pipe 9. Pipe 9 has a valve and a slotted handle 10 to which is affixed adjustably, the rod 10' which is attached to the governor of the engine so that when the load on the engine is increased or diminished, the governor, drawing on rod 10' will more or less open or close valve 10 and increase or diminish the oil supply.

In chamber 1' is the vaporizer 11 attached preferably to casing 1 and arranged to receive the charge of oil and air entering it by means of the valve 3, its exit end or overflow point 70 being elevated or arranged so as to prevent any unvaporized oil from escaping from it after the vaporizer and igniter 11 is once sufficiently heated by the explosions in the cylinder, thus forming a pocket in which the oil is retained until fully vaporized, the vaporized oil and air passing out of the vaporizer and into the ignition device 12 which device is preferably a bent tube 12 attached to chamber 1' preferably by screwing it into a threaded opening therein, the upper end of the ignition tube having a regulating tube 13 attached to it, in order that the time of firing may be regulated. If the firing takes place too early I shorten the tube 13 and if too late I lengthen it, but after the time of firing has been once correctly ascertained and the tube made of the proper length to govern the firing, I close the tube 13 preferably by a cap as it then needs no more attention. The tube 13 is lengthened by turning the cap upward, and shortened by turning it downward, and as, if the tube is cut to the right length the lengthening and shortening may be very slight, the cap is a cheap and adequate device for this purpose.

Under the ignition chamber I set a source of heat, preferably an oil burner of the kind shown, and as it is a burner in common use a detailed description thereof is not deemed necessary. The heat heats the ignition chamber or tube 12 to redness preferably. Surrounding the tube 12 is a jacket 15 lined with a nonconductor 14 preferably, consisting of

asbestos in order to keep the tubes 12 and 13 as hot as possible.

The operation is as follows: The burner 16 being set in operation, the flame is allowed to burn until the ignition tube is heated to redness and until the inner vaporizing tube 11 is heated sufficiently to vaporize the first few charges of oil. The fly wheel of the engine is then revolved until the piston makes one or more suction strokes. As the piston makes a suction stroke, the suction opens or draws down valve 3, the stem 4 and the plunger 5, the plunger acting like a pump, compressing the charge of oil in chamber 18 and forcing it through port 5' down the tubular stem 4, and out through channels 3''' in valve 3, and causing it to be sprayed against the heated sides of vaporizer 11, and at the same time a charge of air is sucked into the vaporizer 11 through opening 19 and the oil, vapor and air are thus mixed in the vaporizer and pass out of it and into tube 12, chamber 1' and the cylinder. On the compression stroke of the piston, the mixed oil vapor and air are compressed and forced back again into ignition chamber 12 and against its red hot sides where it is ignited creating an explosion which operates the piston. To the opening 1'' is fixed the usual exhaust valve used with ordinary gas or oil engines and as their construction is well known, and they being in common use, a detailed description thereof is deemed unnecessary. On the exhaust stroke of the piston the products of combustion are discharged from the exhaust valve in the usual manner. As the explosions continue in the cylinder and in chamber 1' the heat engendered is sufficient to keep vaporizer 11 sufficiently heated to cause it to vaporize any and all oil entering it, the tube 11 acting as a superheater as well as a vaporizer, and after the engine has run for a short time vaporizer and igniter 11 is heated by the explosions in the cylinder to such a degree that it becomes a vaporizer and igniter combined, first vaporizing any oil that may enter it on the suction stroke of the piston, and igniting the mixed vapor and air on the compression stroke, and when so heated the temporary burner 16 may be shut off entirely and the engine continue to run. As vaporizer and igniter 11 is open to the inrush of the products of combustion of each explosion in the cylinder and is also externally surrounded by them, its full surface both exterior and interior are acted on directly by the heat in said products, thus allowing of its being quickly heated to the degree required. The object of having the exit end of vaporizer and igniter 11 project into the supplementary or outer igniter 12 is, that this end may become heated from the external burner 16 at the same time the outer or supplementary igniter 12 is being heated and to also provide an extended surface upon which to vaporize all oil entering vaporizer and igniter 11. The form of vaporizer 11 as shown

may be modified if desired, as I do not confine myself to the form shown.

Having described my invention so that those skilled in the art to which it appertains may make and use the same, what I claim, and desire to secure by Letters Patent, is—

1. In combination with an oil or vapor engine, a chambered inlet valve as —3— having a tubular stem as —4, a plunger as —5—, the plunger and stem being movably set in a chamber as —18—, a port as —5— in the valve stem and an oil supply pipe arranged to supply the chamber with oil substantially as described. 80

2. In a gas, oil or vapor engine, a chamber attached to the engine cylinder and forming practically an extension thereof, said chamber containing a vaporizing device and having an oil supplying valve arranged to supply the vaporizing device with a charge of air and oil, and having an ignition device and a source of heat arranged to heat it, a portion at least of the vaporizing device being inside the ignition device and arranged to receive a part at least of its heat therefrom, and arranged so that on the suction stroke of the piston a charge of oil and of air will pass into and the oil be vaporized by the vaporizer, the mixture of oil vapor and air pass into the engine cylinder and on the compression stroke of the piston be forced into the ignition and vaporizing device and ignited substantially as described. 90

3. An oil feeding valve for oil or vapor engines consisting of a chambered valve having a tubular valve stem in communication with said chamber, the valve stem passing into a chambered body and arranged to move therein, and having a port leading from the chamber in said body to the chamber in the valve and a plunger in the chamber in said body arranged to move with the stem and leave the port open, and an open space about the valve stem in which the plunger moves and an oil supply pipe arranged to supply oil to said open space and arranged so that when the valve is opened the plunger will compress the oil and force it into said valve and out of the same, said valve having outlet openings substantially as described. 100

4. In a gas, oil or vapor engine, a combined vaporizer and ignition device located in the engine cylinder and a second or supplemental ignition device located outside the cylinder, the combined vaporizer and ignition device entering the supplemental ignition device and arranged to receive a portion of its heat through the same and having a source of heat outside the engine cylinder arranged to heat the supplementary ignition device, the combined vaporizer and ignition device having its overflow point arranged to prevent the escape of all liquid oil therefrom and having an intake valve arranged to supply oil to the combined vaporizer and ignition device said combined device being arranged to receive 110

the heat from the explosions in the cylinder directly on its inner and outer surfaces and to be heated thereby to a degree sufficient to ignite the vapor and air in the cylinder on the compression stroke of the piston substantially as described.

5. In a gas, oil or vapor engine an ignition and vaporizing device located in the engine cylinder and a supplemental ignition device located outside the cylinder and a source of heat arranged to heat the supplemental ignition device the internal ignition and vaporizing device being arranged to receive a

part of its heat through the supplemental or outer ignition device and arranged to be 15 mainly heated by the explosions in the engine cylinder and an oil supply valve arranged to supply oil to said inner vaporizer and ignition device substantially as described.

In testimony whereof I affix my signature in 20 presence of two witnesses.

JOSEPH ROBISON.
